UNITED STATES PATENT OFFICE.

RAYMOND W. COOK, OF BRISTOL, CONNECTICUT, ASSIGNOR TO THE WALLACE BARNES COMPANY, OF BRISTOL, CONNECTICUT, A CORPORATION.

CLIP.

Application filed November 10, 1922. Serial No. 600,046.

To all whom it may concern:

Be it known that I, RAYMOND W. COOK, a citizen of the United States, residing at Bristol, in the county of Hartford and State 5 of Connecticut, have invented a new and useful Improvement in Clips; and I do hereby declare the following, when taken in connection with the accompanying drawings, and the characters of reference marked 10 thereon, to be a full, clear, and exact description of the same, and which said drawings constitute part of this application, and represent, in—

Fig. 1 a view in front elevation of a clip 15 embodying my invention.

Fig. 2 an edge view thereof.

Fig. 3 a view thereof in vertical central section, showing one use of it.

Fig. 4 a corresponding view in transverse 20 section on the line 4—4 of Fig. 1.

Fig. 5 a detached view in front elevation of the one-piece, sheet-metal clip-body.

Fig. 6 a view thereof in rear elevation.

Fig. 7 a detached view of the advertising 25 jacket prior to being crimped upon the face-plate of the clip-body.

My invention relates to an improved clip primarily intended for use in fastening printed matter, samples, etc., to letterheads 30 in business correspondence, but available for use in a variety of kindred situations, the object being to produce, at a low cost for manufacture, a simple, convenient, effective and attractive clip constructed with par- 35 ticular reference to tenacity of grip, holding capacity, and to the display of trade-marks and other descriptive or advertising matter, or both.

With these ends in view, my invention 40 consists in a clip having certain details of construction and combinations of parts as will be hereinafter described and pointed out in the claims.

In carrying out my invention, as herein 45 shown, I produce, from a blank of thin, resilient sheet-metal, a clip-body comprising a circular, concavo-convex face-plate 10 and an integral, bowed reach 11 and shank 12 originating at the center of the upper edge 50 of the said plate and turned rearward and downward behind the same, the said shank being enough longer than the diameter of the plate to project below the lower edge thereof, and set on a forward pitch to en- 55 gage the said lower edge and thus form a

wedge-shaped space 13 between it and the concave inner face of the face-plate 10. The said space 13 permits the clip to receive considerable material without tending to "back off" the same, as it were, and "let go." 60 Normally, the shank stands, as shown in Fig. 2, in a plane at an angle to the plane of the plate, from the lower edge of which it must be sprung away, as shown in Fig. 3, for its application, for instance, to a 65 sample, such as the piece of fabric 14, shown in Figs. 3 and 4. When the shank is thus sprung away from the lower edge of the face-plate, it is placed under more or less tension, dependent upon the resiliency of the 70 metal and the extent to which the shank is sprung, which will, in turn, depend upon the thickness of the sample, or other item or items "clipped."

At a point preferably above its center, 75 the face-plate 10 is cut and struck inward to form an upstanding, spring gripping-finger 15, which co-acts with a corresponding spring gripping-finger 16 formed by cutting and setting forward a portion of the 80 shank 11 at a point substantially behind the finger 15 aforesaid, the said fingers 15 and 16 being housed within the space 13. These two fingers are sprung apart when the clip is applied to an item and grip the same, in 85 addition to the gripping-action produced by putting the shank itself under tension, due to springing it for its application to the item. By providing the face-plate with a finger 15, complementing the finger 16 of 90 the shank, I greatly improve the gripping-action of the clip, and, therefore, the stability of its hold. The gripping-action of the fingers 15 and 16 is also supplemented and protected by the "burial," as it were, of 95 the thin edges of the concavo-convex face-plate in the item throughout an area substantially surrounding the said gripping-fingers.

The front face of the face-plate is covered, 100 as shown, and by preference, with a circular advertising-jacket 17 enough larger in diameter than the diameter thereof to have its edges crimped over the same, to form retaining-flanges 18, for its retention there- 105 upon. In its upper edge the jacket is formed with a wide clearance-notch 19 for the clearance of the bowed reach 12 of the shank 11 at the point where the same originates on the plate 10, while the lower edge of the 110

jacket is formed with a corresponding clearance-notch 20, to facilitate the crimping of the jacket upon the face-plate. The provision of the jacket with the notch 20 also facilitates the removal of the clip from whatever it may be clipped upon, since it exposes the center of the lower edge of the plate, which is slightly lifted at this point by an indentation 21, whereby the plate is easily engaged by the finger-nail of the user. The said notches 19 and 20 are as wide as, or wider than, the said shank, which they accommodate, as described. It is intended that the jacket shall be made of celluloid, or other corresponding material adapted to be readily crimped upon the face-plate and also adapted to receive printing of a descriptive or trade-mark character, or both. Of course, the printing or reading matter imposed upon the jacket will widely vary,—as widely as the uses to which my improved clip may be put. In case the jacket is omitted, a trademark or other matter may be impressed directly upon the face-plate.

25 I claim:

1. As a new article of manufacture, a clip made of resilient sheet-metal and comprising a face-plate and an integral shank originating at the upper edge thereof, and extending downwardly behind the same, the said plate and shank being furnished with gripping-fingers set into the space formed between the plate and shank arranged in line opposite each other and directly co-acting in discharging their gripping function.
2. As a new article of manufacture, a clip made of resilient sheet-metal and comprising a concavo-convex, circular face-plate and an integral shank located behind the same and connected therewith by a bowed reach, the said plate and shank being cut and struck up to form spring gripping-fingers located within the space formed between the plate and shank arranged in line opposite each other and directly co-acting in discharging their gripping function.
3. As a new article of manufacture, a clip

having a resilient clip-body comprising a face-plate and an integral shank located behind the same, one of the said parts having a spring gripping-finger located in the space between them, and the said face-plate being provided with an advertising-jacket having its upper edge cut away to clear the shank at the point where the same originates on the edge of the face-plate, and having its lower edge cut away to form a clearance-notch corresponding to the width of the said shank and receiving the same.

4. As a new article of manufacture, a clip having a resilient, sheet-metal clip-body comprising a concavo-convex, circular face-plate and an integral shank located behind the same, one of the said parts being formed with a spring gripping-finger set into the space between them, and the said face-plate being provided with an advertising-jacket crimped over its edges and formed with clearance-notches for the clearance of the shank where it originates at the edge of the face-plate and where it makes contact therewith.

5. In a clip, the combination with a resilient, sheet-metal clip-body, comprising a concavo-convex, circular face-plate and an integral shank located behind the same, of co-acting, spring gripping-fingers cut from the said plate and shank and set inwardly into the space between the same; and a circular advertising-jacket crimped over the said face-plate and formed in its upper and lower edges with clearance-notches for the clearance of the said shank where it originates upon the upper edge of the plate and where it makes contact with the lower edge thereof.

In testimony whereof I have signed this specification in the presence of two subscribing witnesses.

RAYMOND W. COOK.
